CLAIM

The ornamental design for a ceiling fan, as shown and described.

DESCRIPTION

FIG. 1 is a bottom view of a ceiling fan;
FIG. 2 is a rear view of the ceiling fan;
FIG. 3 is right side view of the ceiling fan;
FIG. 4 is a front view of the ceiling fan;
FIG. 5 is a left side view of the ceiling fan;
FIG. 6 is a perspective view of the ceiling fan; and,
FIG. 7 is a top view of the ceiling fan.
Broken lines depict portions of the ceiling fan that form no part of the claimed design.

1 Claim, 7 Drawing Sheets
